UNITED STATES PATENT OFFICE.

CARLO YENNOW, OF PRINCE ALBERT, SASKATCHEWAN, CANADA.

DESIGN FOR AN ELECTRIC LAMP.

52,517.

Specification for Design.

Patented Oct. 1, 1918.

Application filed June 26, 1918. Serial No. 242,117. Term of patent 3½ years.

To all whom it may concern:

Be it known that I, CARLO YENNOW, a citizen of Russia, and a resident of Prince Albert, in the Province of Saskatchewan, Dominion of Canada, have invented a new, original, and ornamental Design for Electric Lamps, of which the following is a specification, reference being had to the accompanying drawing, forming a part thereof.

The figure is a front elevational view of the electric lamp, showing my design.

I claim—

The ornamental design for an electric lamp as shown.

CARLO YENNOW.
